FIG. 4.

UNITED STATES PATENT OFFICE.

LEON W. RITTENHOUSE, OF ROCHESTER, NEW YORK.

SNOWPLOW.

Application filed April 17, 1924. Serial No. 707,175.

To all whom it may concern:

Be it known that I, LEON W. RITTENHOUSE, a citizen of the United States of America, residing at Rochester, in the county 5 of Monroe and State of New York, have invented certain new and useful Improvements in Snowplows, of which the following is a specification.

This invention relates to certain new and 10 useful improvements in snow plows and particularly to the type where a plow or snow removing device is positioned forwardly of a standard construction of tractor, such as a Fordson tractor for clearing a path or removing snow from a roadway or the like.

A further object of the invention is to 15 provide in a snow plow of the type above set forth the provision of operating mechanism for the plow structure driven by devices associated with the motor of the tractor and under control of the operator.

A further object of the invention is to 20 support the plow structure forwardly of the tractor by brace bars and to provide a skid at each side of the plow structure to assist in the support thereof and to retain the same properly positioned with relation to the tractor.

A further object of the invention embodies 25 the provision of a novel type of bearing or hub for the snow gathering or removing bladed wheel of the plow structure to insure a perfect operation.

The invention further embodies certain 30 improvements in the art to which it relates and more particularly with reference to the patent granted to L. W. Rittenhouse on snow plow, Patent No. 1,406,897, dated February 14, 1922.

With the above and other objects in view 35 and others that will appear as the nature of the invention is better understood, the same consists of the novel form, combination and arrangement of parts hereinafter more fully 40 described, shown in the accompanying drawings and claimed.

In the drawings, wherein like reference 45 characters designate corresponding parts throughout the several views,

Figure 1 is a side elevational view of a 50 snow plow constructed in accordance with the present invention, the operating mechanism therefor being illustrated as associated with a tractor that is illustrated by dotted lines,

Figure 2 is a top plan view of the same,

Figure 3 is a vertical cross-sectional view taken on line III—III of Fig. 1 showing the side supporting skids for the plow structure,

Figure 4 is a detail plan view showing the operating mechanism for the snow gathering wheel, and

Figure 5 is a longitudinal sectional view of the hub or bearing for the snow gathering wheel.

The snow plow is positioned forwardly of the tractor 1 illustrated by dotted lines in Figs. 1, 2 and 4 and embodies a snow gathering wheel having operative connections 70 with the motor 2 of the tractor. The plow includes a casing or hood structure in the form of a housing having a rear wall 3 of the form best illustrated in Fig. 3, a side wall 4 curved at its upper end as at 5 and merging into the flat upper wall 6 while the opposite side wall 7 is outwardly curved adjacent its upper end and terminates at the point 8 to form a lateral discharge opening 9. The side wall 4 carries a forwardly directed plate extension 10 and the lower wall of the housing includes a downward extension 11 carrying a forwardly directed foot or shovel 12 adjacent the ground line as illustrated in Fig. 1. A curved hood 13 is 85 carried by the side and upper wall sections 4, 5 and 6 to prevent an upward throw of the gathered snow and to assist in directing the same through the discharge opening 9. The housing of the plow structure is supported upon the tractor by brace bars 14 and 15 of the type best illustrated in Figs. 1 and 2.

A further support for the plow structure in the form of shoes or skids is associated therewith, angle brackets 16 being carried by the rear corner edges of the housing adjacent the upper and lower ends thereof and through which vertical shafts 17 extend, the lower angle brackets 16 carrying depending bearings 18 for the shafts 17 while skid shoes 19 in the form of disks are carried by the lower ends of the shafts. It will therefore be seen that the plow structure has the skid shoe supports in addition to the brace bars 14 and 15 and insure the proper positioning of the shovel edge 12 with relation to the ground line.

The housing being open at its forward side, the snow received therein during the forward travel of the housing is laterally discharged through the opening 9 by a

bladed wheel mounted upon a hub structure of the type illustrated in Fig. 5 wherein a fixed hub member 20 having an end flange 21 secured as at 22 to the rear wall 3 of the housing provides a bearing for the axle or shaft 23 passing through the hub member 20 and spaced therefrom by the relatively long sleeve 24 positioned centrally of the hub member. Roller bearing 25 engaging the shaft 23 adjacent each end thereof are located at each end of the collar 24 and are set into cutaway portions 20^a provided in the inner face of the hub member 20, the bearing rollers 25 being enclosed by a collar 26. An outer hub member 27 carrying the snow gathering wheel blades 28 has the reduced closed bearing end 29 thereof keyed as at 30 to the projecting tapered end of the shaft 23 and retained in position thereon by the jamb nuts 31 threaded on the extension 23^a of the shaft. An annular flange 32 is carried by the larger end of the outer hub member 27 and is disposed adjacent the flange 21, while ball bearings 33 are interposed between the larger end of the hub member 27 and the rear end of the inner hub member 20.

The operating means for the bladed snow gathering wheel includes a relatively large gear 34 keyed as at 35 to the rear projecting end of the shaft 23 and is positioned rearwardly of the housing of the plow structure and meshes with the pinion 36 carried by the stub shaft 37 that is journaled in the bracket 38 carried by the rear wall 3 of the housing as clearly illustrated in Figs. 1 to 3. A casing 39 housing clutch mechanism under control of the lever and link mechanism 40 also encloses meshing gears 41 and 42, the gear 41 being carried by the stub shaft 43 journaled in the forward wall of the casing 39 and carrying a gear 44 upon the projecting end thereof aligned with the gear 45 upon the power shaft 46 of the motor 2 as shown in Fig. 4, a chain 47 connecting the gears 44 and 45 for transmitting power to the gears 41 and 42 and the clutch mechanism in the casing 39. A stub shaft

47' journaled in the forward wall of the casing 39 supports the gear 42 and a rod 50 48 has a universal connection 49 at its opposite ends with the stub shafts 37 and 47.

From the above detail description of the snow plow, it is believed the construction and operation thereof will at once be apparent, it being noted that power is transmitted from the main shaft 45 of the motor to the bladed snow gathering wheel through the chain and gear mechanism above described under control of the clutch devices in the casing 39. The bearing for the snow gathering wheel insures perfect operation thereof as the bearing elements are fully protected from the snow and the skid shoes 19 assist the brace rods 14 and 15 in properly supporting the plow structure with relation to the ground line and insuring even travel thereof over a road surface.

While there is herein shown and described the preferred embodiment of the present invention, it is nevertheless to be understood that minor changes may be made therein without departing from the spirit and scope of the invention as claimed.

What is claimed as new is:—

The combination with a tractor and its motive power unit, of a snow gathering, bladed wheel carried by and located forwardly of the tractor, a gear connected to said wheel to rotate therewith, a pinion meshing with the gear, a casing carried by the tractor, a stub shaft journaled in the casing and projecting therefrom, a sprocket wheel on the projecting portion of the stub shaft, a sprocket wheel on the front end of the crank shaft of the motive power unit for the tractor, a chain connection for said sprocket wheels, a gear on the stub shaft within the casing, a clutch controlled connection between the stub shaft and the gear within the casing, and a drive connection between the last mentioned gear and the pinion.

In testimony whereof I affix my signature.
LEON W. RITTENHOUSE.
